(57) **CLAIM**

The ornamental design for a motorcycle fairing scoop trim, as shown and described.

DESCRIPTION

FIG. 1 is a top perspective view of the motorcycle fairing scoop trim of the present invention.

FIG. 2 is a right side elevation view of the motorcycle fairing scoop trim of FIG. 1.

FIG. 3 is a left side elevation view of the motorcycle fairing scoop trim of FIG. 1.

FIG. 4 is a front elevation view of the motorcycle fairing scoop trim of FIG. 1.

FIG. 5 is a rear elevation view of the motorcycle fairing scoop trim of FIG. 1.

FIG. 6 is a top plan view of the motorcycle fairing scoop trim of FIG. 1; and,

FIG. 7 is a bottom plan view of the motorcycle fairing scoop trim of FIG. 1.

The broken lines indicate that the rear surface of the horizontal portion and the interior surface of the vertical fin portions form no part of the claimed design.
